MEANS FOR MAKING BELL-ENDED PIPES
BY CENTRIFUGAL CASTING

Jacques Boucher, Paris, France, assignor to Compagnie de Pont-a-Mousson, Nancy (M. & M.), France, a French company

Original application February 28, 1946, Serial No. 650,914. Divided and this application July 16, 1947, Serial No. 761,216. In France December 23, 1943.

Section 1, Public Law 690, August 8, 1946
Patent expires December 23, 1963

1 Claim. (Cl. 22—65)

1

This invention relates to a centrifugal casting apparatus, and is a division of my copending application, Ser. No. 650,914, filed February 28, 1946, which has been abandoned.

The manufacture of bell-ended pipes by centrifugal casting is in current use. The shape of the flared end of the pipe is obtained by means of a core placed at the end of the mould before casting each pipe. By reason of the contraction of the metal in the course of its solidification, recourse has generally been had to cores made from a refractory material, such as the usual foundry sand. The labor and materials necessary for making such cores, and the time occupied in putting them in position, obviously affect the cost of the moulded pipes. The method of manufacturing according to the present invention enables the rate of production to be increased.

According to the invention, there is made by centrifugal casting a pipe of which the external surface of one of its ends is directly given in a known manner the final bell-like shape, while internally the pipe is made cylindrical throughout its length, the mould comprising at this end a detachable dam applied against the mould face, the inner diameter of said dam being equal to the inner diameter of the pipe to be cast, and the bell-end of said pipe being internally hollowed out, and screw threaded if required by subsequent machining.

This method of manufacturing enables the cores usually employed for forming the inner hollow of the pipe bell-end to be completely eliminated. The dam for closing the mould is preferably made of metal, and therefore its wear is reduced. Moreover, this dam may further serve to cast a great number of pipes, and may therefore be mounted on a self-acting mould-closing device such as that hereinafter described by way of example, whereby the rate of production can be increased. This method of manufacturing is especially advantageous in casting pipes of small diameter, where the quantity of metal to be removed by the machine tool is not too large.

Other features of the invention will be apparent from the following description.

The invention is illustrated by way of example in the accompanying drawings in which:

Fig. 1 is a longitudinal sectional view showing

2

a detachable mould dam according to the invention;

Fig. 2 is a front view showing a support for a detachable mould dam according to another embodiment of the invention;

Fig. 3 is a longitudinal view, half in elevation and half in section, showing a detachable mould dam mounted in the support of Fig. 2;

Fig. 4 is a plan view showing self-acting means for removing the detachable mould dam according to the invention.

Referring to Figure 1, 1 denotes a cast pipe, while 2 (cross-hatched parts of the drawing) denotes the internal hollow of the pipe bell-end, as it usually appears from the casting operation. According to the invention, the pipe is cast with its internal surface made cylindrical throughout its length along the generating line 3, the hollow 2 being machined subsequently. In order to shape the pipe end, there is engaged in a recess 4 provided at the end of the chill mould 5 a dam 6, which is kept pressed against the mould end by means of a number of heel keys 7, the bodies of which engage in openings 8 provided in a mould collar 9, while their heels press against the dam 6. Such a fastening arrangement assures full safety, since the centrifugal force due to the rotation of the mould tends to tighten the grip of the said keys. The inner surface of the pipe 1 is determined by the diameter of the central hole of said dam, through which overflows a little excess of molten metal. In order to release the solidified pipe 1, the keys 7 and the dam 6 are removed, and will be put in again for the next casting operation.

Referring now to Figure 2, 15 denotes the end of a rotary mould, and 16 its stationary support, in which the mould is adapted to rotate, while 17 denotes the movable dam intended to be pressed against the mould end 15, this dam being mounted to rotate in an annular casing 20 supported by two trunnions or journals 21, 22 in a bracket or support 23 adapted to oscillate about a pivot 24 mounted on the mould-supporting member 16. The support 23 is provided with an operating handle 25, and is held immovable in its closed position by any suitable locking means mounted fast on the mould-supporting member 16 and diagrammatically shown at 26.

The operation of this apparatus is as follows:

When the apparatus is closed, that is to say, the dam 17 being applied against the mould end 15, and the locking means 26 being in closed position, the casting operation is effected while the mould is in rotation. As the dam 17 can rotate in its annular casing 20, it is constrained to rotate together with the mould against which it is applied. The two journals 21 and 22 of the casing 20 permit the latter to adjust itself and the dam to bear against the mould face 15. When the pipe is sufficiently solidified, the latch 26 is unlocked and the support 23 opened by tilting it about its pivot 24. The mould face 15 is thus released, and the pipe can be extracted, after which the apparatus is closed again so that the next casting operation may be effected in the same way as before.

An example of a movable dam mounted in its casing is shown in Figure 3, wherein the movable dam properly so called is shown at 17. This dam is supported by a piece 32, on to which it is screwed at 31, gripping the inner race 33 of a ball bearing, the outer race 34 of which is lodged in the body of the casing 20 and maintained in its position by a cover 37, pressed thereupon by means of screws 38. The casing 20, as already shown in Figure 2, is supported by two trunnions or journals 21 and 22, adapted to rotate in the support 23 through the medium of silent-blocks 41, maintained by notched nuts 42 screwed on to the threaded ends of the said journals. The composite unit comprising the piece 32 and the dam 17, supported solely by the inner race 33 of the ball bearing, can rotate within the casing 20. In the latter is provided a chamber 43 for receiving a fluid under pressure (water or air) intended for cooling, this chamber being closed by a welded cover 44, and communicating through ducts 45 with ducts 46 formed in the movable piece 32 and opening into a chamber 47, which communicates through bores 48 with evacuation holes 49 disposed between ribs 50 provided on the movable dam 17. Stuffing leather elements 51, 52, 53 and 54 are lodged in grooves. A sheet-metal guard 58 is welded to the end of the casing 20, to prevent the excess of liquid metal which overflows through the dam splashing out during the casting operation.

The operation of this apparatus has already been explained in connection with Figure 2. The silent-blocks readily enable a certain resilient pressure of the dam 17 to be exerted against the mould 15. The ribs and the fluid-circulation ducts facilitate the cooling of the dam 17 in contact with the mould 15.

Finally, in Figure 4 is diagrammatically shown a self-acting device for removing the movable dam from the mould end. In this figure, 61 denotes the frame supporting the rotatable mould, while 62 denotes the support for the movable dam 63 mounted as previously described. The support 62, which can swing about a pivot 64 mounted fast on the frame 61, is maintained in the closing position shown in the drawing by a latch 66, the pivot 67 of which is likewise fixed to the frame 61. This latch is maintained in its locking position by a spring diagrammatically shown at 68. By 69 is denoted a fixed abutment on the general base of the casting machine as a whole, since the frame 61 supporting the mould is subjected to a movement of translation parallel to its longitudinal axis.

The operation of this latter apparatus is as follows: Whilst the casting operation is going on in the rotating mould, the latter is displaced

along its longitudinal axis. When the mould attains the end of its stroke the pipe-casting operation is terminated, and the rear arm of the latch 66 comes into contact with the abutment 69, which opens the latch and liberates the support 62, which, when the frame 61 is stopped, keeps on moving by inertia, and consequently opens by pivoting about the pivot 64. This opening movement of the support 62 is facilitated by the disposition of the pivot 64; indeed, as the latter is parallel to the end surface of the mould, and as the whole mould assembly is slightly inclined to the horizontal plane, the pivot 64 itself is slightly inclined with respect to the vertical plane, so that the support 62 and the whole mechanism carried thereby are acted upon by gravity in the opening direction. Otherwise, an opening spring might be added thereto, if it were necessary.

It will be understood that the invention is not limited to the particular embodiments described and shown, which have been set forth merely by way of example. Thus, the mould dam under consideration, instead of being of metal, might be made from any suitable refractory material. Instead of being fastened by means of heel keys as described above, the dam may be fastened by screws or the like. In one modification described above the mould dam is rotatably mounted in its support by means of a single ball bearing with deep grooves, but it is evident that several ball bearings, or even ball-and-socket or swivel bearings, may be used instead.

Cooling by water, air or any other fluid, instead of being effected from within, may be effected from without, for example, by means of external jets.

The support for the ring, mounted on a single articulation, may be provided with a double articulation, for example, of the universal joint type.

The opening displacement of the support, instead of being effected about a substantially vertical axis, may be effected by making it give way longitudinally with a subsequent lateral, vertical or combined translation.

Finally, the opening device may be operated manually, electro-magnetically, pneumatically or otherwise, without thereby going outside the scope of the invention.

I claim:

In a centrifugal mould for casting bell-ended pipe of the type wherein the internal diameter of the pipe is constant throughout its length, a dam mechanism for the end bell portion of the mould comprising in combination, a removable annular dam and an annular casing member surrounding said dam, said dam being rotatably supported in said casing member; said dam and casing member having cooling chambers therein and ducts in said members connecting said chambers; spaced, deformable sealing elements secured between the opposing surfaces of said dam and casing members, said ducts opening into the space between said sealing elements; said dam having annular heat dissipating ribs about its body, one of said cooling chambers being disposed adjacent said ribs, and passages in said body between said ribs connecting said last named chamber to the atmosphere.

JACQUES BOUCHER.
